UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 5, 1921. Serial No. 449,754.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to paper-carrying 10 devices of typewriting machines, and is shown applied to an Underwood front-strike machine.

One of the objects of the invention is to facilitate the typing of short work or bill- 15 sheets calling for entries upon only two or three lines, as in the case of gas bills. Where but a few entries are to be made, and a large number of work or bill-sheets are to be typed, it is not satisfactory to insert 20 the sheets from the rear and adjust them to typing position, as these operations consume a great deal of time in proportion to the amount of actual typing. The present invention simplifies the introduction of the 25 work-sheets and their adjustment to the printing position.

In carrying out the present invention, the work-sheets are inserted at the front of the platen bottom end foremost. Their upper 30 ends are collated upon a table adjustably mounted on the machine in such position that, when a work-sheet is aligned at its top and side edges on gages carried by the table, the work-sheet will be properly positioned 35 at the printing point. Since the headings (the distance from the upper edge to the first line to be typed) of various types of work-sheets vary in length, means are provided for rapidly adjusting the end gage 40 of the collating table forwardly or rearwardly of the machine, and hence toward or away from the upper edge of the work-sheet. The adjusting means is capable of being moved rapidly through distances equal 45 to full line-spaces or to fractions of a line-space. The collating table is capable of being swung by means of a finger-piece to an inactive position.

The work-sheets having been adjusted in 50 position, means are provided whereby said sheets may be typed upon one, two or three lines. For this purpose, the end gage of the collating table is mounted upon a slide- 55 able plate adapted to be moved upwardly and held in position at line-space intervals,

the sheets, which are held to the table by spring-fingers, being moved up by hand to the end gage in its raised positions. By the above-described means, a simple, rapid, and efficient method of typing short work-sheets 60 is obtained.

Other features and advantages will hereinafter appear.

In the accompanying drawings,

Figure 1 is a front view of a machine, 65 with the invention applied thereto, only the necessary co-operating parts of the machine being shown.

Figure 2 is an end view, partly sectioned, 70 of the device shown in Figure 1, the collating table being in its extreme forward position.

Figure 3 is an end view of the device 75 shown in Figure 1, the collating table being in its extreme rearward position.

In the Underwood standard typewriting machine, a platen 10 is fixed upon an axle 11 journaled in the end walls 12 of a shiftable platen-frame forming part of the usual typewriter carriage. 80

A collating table, indicated generally at 20, is mounted on the platen-frame by means of a rod 21 supported on the end walls in the following manner: The ends of rod 21 are seated in sockets in the collars 22 and 23 of end members or journals 24 and 25. The journals are of the same diameter as the rod 21, and are mounted in the U-shaped supports 26 and 27 fixed on the end walls 12 of the platen-frame. The journals 24 and 25 are each provided with a longitudinal 85 groove, the two grooves being in alignment, and detents 28 and 29, vertically slidable in supports 26 and 27, are pressed against said members 24 and 25 and adapted to lodge in the grooves to hold said members, and hence 90 the rod 21, firmly in position.

The rod 21 is also provided with a longitudinal groove 21^a in which are adapted to seat spring-pressed detents 30 carried by 100 U-shaped supports 31 in a similar manner to those of supports 26 and 27. Supports 31 are carried by brackets 32 fixed to the rear wall 33 of the table by screws 34. Since the position of the collating table varies, as will be described later, the spring-pressed detents will not lodge in the groove in rod 21 unless the rod is turned through the same angle as the table at each change of position. For this purpose, the rod 21 may be rotated 110

in the collars 22 and 23 on the end members 24 and 25 by loosening screws 35, which fasten the rod 21 in the collars. When the rod has been adjusted to proper position, the screws are tightened, and the end members and rod 21 again move as a unit. A finger-piece 36 is fixed by screw 37 to one end of an end member, and, by actuating this finger-piece, the rod 21 and the collating table may be rotated forwardly to effective position or rearwardly to ineffective position.

A work-sheet may be inserted at the front of the platen bottom end foremost until the first line to be typed is at the printing point, the upper end of the sheet resting upon the collating table. The latter may be moved forwardly or rearwardly until an upper end gage 40 comes in contact with the leading edge of the work-sheet. The table is then fixed in position, and thereafter work-sheets of the same variety inserted at the front of the machine need only have their leading edges positioned in contact with the upper end gage 40, and the sheets will be properly positioned to type the first line. The work-sheets may be gaged at one side edge by a side-edge gage 50 on table 20. The means enabling the collating table to be moved forwardly and rearwardly and to be fixed in adjusted position are now to be described.

The end supports 26 and 27, carrying the journals 24 and 25 and rod 21 with its collating table, are fixed to base-blocks 41 and 42, respectively, through which are threaded screws 43 and 44. The lower ends of the screws operate in forwardly and rearwardly extending slots 45 in plates 46 fixed by screws 47 to the tops of the platen-frame end walls. The lower ends of the screws 43 and 44 are threaded into nuts 48, larger than the slots 45 to prevent withdrawal of the nuts. Shoulders 49 on screws 43 and 44 may be screwed down to press upon the upper surface of the base-blocks 41 and 42, to hold the latter firmly in position against the plates 46. By unscrewing screws 43 and 44, the blocks 41 and 42 are free to move forwardly or rearwardly, carrying the collating table nearer or further from the leading edge of the work-sheet.

Where more than one line is to be typed, means must be provided for suitably gaging such sheets at line-space intervals. The line-spacing is accomplished by mounting the end gage 40 on a slidable plate 60 between a top plate 62 of the collating table and a bottom or rear bar 61. The plate 62 is fixed to the rear bar 61 by screws 63 countersunk in the top plate, the countersunk portion of plate 62 providing clearance between the top plate and the rear bar for the slidable plate 60. The latter has cut-out portions 64 adapted to clear the screws 63 when it is moved upwardly. For moving

the slidable plate upwardly, a finger-piece 65 fixed thereto is moved toward the left. Pins 66 fixed to the top plate 62 project into cam-slots 67 provided with dwells 68 at their ends. When finger-piece 65 is moved toward the left, plate 60 rides upwardly on pins 66. A spring 70, fixed to the rear bar, is provided with a pin 71 adapted to project through an opening in said rear bar and press against the slidable plate. Three openings 72, 73, and 74 are provided in plate 60 corresponding to the lowest and two raised positions of the plate, each raised position being one line-space position above the previous position. The pin 71, lodging in the openings 72, 73, and 74, will hold the plate 60 in each position, and, in addition, the pins 66, riding on dwells 68, will hold the plate 60 firmly in lowest and highest positions. Where more than three lines are to be typed, longer cam-slots 67 and more openings, similar to 72, 73, and 74, may be provided. Spring-fingers 75, attached to the rear plate and bent over to contact with the front plate, aid in holding the work-sheets in position. The loops of the springs are sufficiently large not to interfere with the upward movement of the slidable plate.

Variations may be resorted to within the scope of the invention, and portions of the improvements may be used without others.

Having thus described my invention, I claim:

1. In a front-strike typewriting machine, a platen, and means settable for rapidly locating on the platen in succession a plurality of work-sheets having the same depth of heading, comprising a collating table at the delivery side of the platen, a leading-edge gage, and a support for said table shiftable forwardly and rearwardly to vary the distance between the leading-edge gage and the writing line in accordance with the depth of heading on the set of work-sheets to be inserted.

2. In a front-strike typewriting machine, a platen-frame provided with end walls, a platen supported in said walls, a collating table at the front of the platen having a leading-edge gage, and supports slidably mounted on the end walls of the platen-frame to be shifted forwardly and rearwardly to vary the distance of the leading-edge gage from the printing line to correspond with the depth of heading on a plurality of work-sheets to be inserted and typed upon in succession.

3. In a front-strike typewriting machine, a platen-frame provided with end walls, a platen supported in said walls, a rod above the platen, supports for said rod mounted for forward and rearward sliding on said end walls, and a collating table rotatably mounted on said rod and having a leading-edge gage, whereby said rod and said table

may be shifted forwardly and rearwardly to vary the distance of the leading-edge gage from the printing line.

4. In a front-strike typewriting machine, 5 in combination, a platen-frame having end walls, a cylindrical platen supported in said end walls, a rod mounted above said platen, supports for said rod fixed on said end walls, a collating table rotatably mounted on said 10 rod and having a leading-edge gage movable by line-space intervals with respect to said table, means whereby said rod and said table may be shifted forwardly and rearwardly to vary the distance of the leading-edge gage 15 from the printing line, and means permitting adjustment of said rod to vary the inclination of the table to compensate for the forward and rearward adjustment of the rod and table.
- 20 5. In a front-strike typewriting machine, in combination, a platen-frame having end walls, a cylindrical platen supported in said end walls, a rod mounted above said platen, supports for said rod, a collating table rotatably mounted on said rod and having a leading-edge gage movable by line-space intervals with respect to said table, a sliding connection between each of said supports and the corresponding end wall to permit 25 said rod and said table to be shifted forwardly and rearwardly to vary the distance of the leading-edge gage from the printing line, a readily releasable device for clamping each of said supports in adjusted position, and means permitting adjustment of 30 said rod to vary the inclination of the table to compensate for the forward and rearward adjustment of the rod and table.
6. In a front-strike typewriting machine, 40 in combination, a platen-frame having end walls, a cylindrical platen supported in said end walls, a rod mounted above said platen, supports for said rod, a collating table rotatably mounted on said rod and having a leading-edge gage movable by line-space intervals with respect to said table, a sliding connection between each of said supports and the corresponding end wall to permit 45 said rod and said table to be shifted forwardly and rearwardly to vary the distance of the leading-edge gage from the printing line, means to secure said supports in adjusted position, means permitting adjustment of said rod to vary the inclination of 50 the table to compensate for the forward and rearward adjustment of the rod and table, means for securing the rod in adjusted position, and yieldable means to hold the table in effective position on said rod, but permitting rotation of the table to ineffective position when desired.
7. In a front-strike typewriting machine, 60 in combination, a platen-frame having end walls, a cylindrical platen supported in said end walls, a rod above the platen, journals 65 mounted on the ends of said rod, supports mounted on the end walls of said platen-frame for supporting said journals, a collating table rotatably mounted on said rod and having a leading-edge gage movable by 70 line-space intervals with respect to said table, means whereby said rod and said table may be shifted forwardly and rearwardly to vary the distance of the leading-edge gage from the printing line, and yielding means 75 to prevent said journals from turning in said supports, said rod being revolubly adjustable relatively to said journals to vary the inclination of said table to compensate for the forward and rearward adjustment of the rod 80 and table.
8. In a front-strike typewriting machine, 85 in combination, a platen-frame having end walls, a cylindrical platen supported in said end walls, a rod above the platen, journals 90 mounted on the ends of said rod, a pair of forwardly and rearwardly extending plates fixed on the end walls of the platen-frame, each of said plates having a longitudinal slot, a pair of supports for supporting said journals, means to fasten said supports at different positions along said plates, and a collating table rotatably mounted on said rod and having a leading-edge gage movable 95 by line-space intervals with respect to said table, the shifting of said supports on said plates operating to shift said rod and collating table forwardly and rearwardly to vary the distance of the leading-edge gage 100 from the printing line.
9. In a front-strike typewriting machine, 105 in combination, a platen-frame having end walls, a cylindrical platen supported in said end walls, a rod above the platen, journals 110 mounted on the ends of said rod, a pair of forwardly and rearwardly extending plates fixed on the end walls of the platen-frame, each of said plates having a longitudinal slot, a pair of supports for supporting said journals, means to fasten said supports at different positions along said plates, a collating table rotatably mounted on said rod and having a leading-edge gage movable by 115 line-space intervals with respect to said table, the shifting of said supports on said plates operating to shift said rod and collating table forwardly and rearwardly to vary the distance of the leading-edge gage from the printing line, and yielding means to prevent said journals from turning in said supports, said rod being revolubly adjustable relatively to said journals to vary the inclination of said table to compensate for the forward and rearward adjustment of the rod 120 and table.
10. In a front-strike typewriting machine, 125 in combination, a cylindrical platen, and means settable for rapidly locating on the platen in succession a plurality of worksheets having the same depth of heading,

comprising a collating table at the delivery side of the platen and having a leading-edge gage, and supporting means for said collating table shiftable horizontally, forwardly and rearwardly, to vary the distance of the leading-edge gage from the printing line, and permitting adjustment of the inclination of the table to render it tangential to said platen in any of said positions.

- 10 11. In a front-strike typewriting machine, in combination, a cylindrical platen, a platen-frame having ends, and means settable for rapidly locating on the platen in succession a plurality of work-sheets having the same depth of heading, comprising a rod above said platen, supports for said rod movable forwardly and rearwardly on said ends of the platen-frame, a collating table mounted on said rod and having a leading-edge gage movable by line-space intervals with respect to said table, and means permitting adjustment of the table around the axis of said rod to vary the inclination of

the table to compensate for the forward and rearward movements of the rod and table. 25

12. In a front-strike typewriting machine, in combination, a platen, a platen-frame having ends, and means settable for rapidly locating on the platen in succession a plurality of work-sheets having the same depth of heading, comprising a collating table at the front of the platen having a leading-edge gage, supports for said table on the end walls of the platen-frame, said supports being shiftable forwardly and rearwardly to vary the position of the table in accordance with the heading of a work-sheet to be inserted, the leading-edge gage being adjustable to different line-space positions on said table to enable the work-sheet to be gaged for lines other than the one for which it was gaged when first inserted into the machine. 30 35 40
